ROBERT T. ROMINE, OF MOUNT CLEMENS, MICHIGAN

PORTABLE PLATFORM

Application filed September 3, 1936. Serial No. 133,371.

This invention relates to portable platforms and especially to that class of platforms adapted to be used with lift trucks wherein the truck is provided with a load elevating platform capable of being introduced beneath the floor of the platform to elevate the platform and its load and transport it from place to place.

An object of the invention is to provide an improved platform which will be relatively simplified in construction enabling it to be manufactured at a relatively low cost, while at the same time being strong and durable and capable of sustaining with safety extremely heavy loads, such as loads of five, ten or fifteen tons.

Other objects of this invention will appear in the following description and appended claims, reference being had to the accompanying drawings forming a part of this specification, wherein like reference characters designate corresponding parts in the several views.

Fig. 1 is a side elevation illustrating a platform embodying my invention.

Fig. 2 is a top plan view thereof.

Fig. 3 is an end elevation showing the lift truck in position beneath the platform with the platform elevated on the truck.

Fig. 4 is a side elevation of a somewhat modified form of my invention.

Fig. 5 is a side elevation showing another form of the invention.

Fig. 6 is a fragmentary end elevation of the construction shown in Fig. 5.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed herein is for the purpose of description and not of limitation, and it is not intended to limit the invention beyond the terms of the several claims hereto appended or the requirements of the prior art.

Portable platforms which are used under present day conditions in connection with power driven electric lift trucks are required to sustain wide variations in loads, ranging anywhere from several tons to twelve and even fifteen tons in weight. In addition the loads are not always centred on the platforms and the drivers of the electric trucks seldom use care in propelling the trucks beneath the platforms, frequently striking the legs and subjecting them to severe blows. Furthermore it frequently happens that the platforms with their loads are placed on uneven ground so that the floor of the platform will not be level. In such cases when the truck platform is introduced beneath the floor boards and elevated, one end edge or portion of the floor will frequently receive at first the entire upward thrust, subjecting it to severe strain which heretofore resulted frequently in breaking off the floor boards at the end of the platform.

It is therefore important in providing a commercially satisfactory platform not only to reduce to a minimum the cost of manufacture but also the weight of the platform, while constructing the platform in such a way as to withstand the various conditions of use and loads of any weight within a wide range.

It is also important that the load be distributed to the greatest possible extent from the floor boards through the legs, that the upward thrust of the truck platform be sustained and distributed uniformly from end to end of the platform, and that the legs be constructed to sustain loads whether centred or not and whether the platform is supported on level or uneven ground. In addition it is important that the legs be constructed to withstand impacts in any direction from the trucks or as the result of collisions while the platforms are being transported from place to place.

The portable platform in the present instance comprises a load supporting floor 9 which preferably is formed of a series of cross boards. The platform floor is bounded around its marginal edges by means of a metal frame comprising angle bars 10 embracing or confining the longitudinal edges of the floor 100

and transverse angle bars 11 confining the end edges of the floor.

Referring to Figs. 1 and 3, a supporting truss 12 extends lengthwise beneath the platform floor at each longitudinal side thereof and in this instance the truss comprises an angle bar having a vertical guide flange 12^a and an inwardly extending horizontal flange 12^b which may be riveted to the floor boards at 12^c by means of countersunk rivets. The angle bars 12 extend in parallel relation the entire length of the platform, and the vertical flanges 12^a provide guide means for the lift platform L of a lift truck T when the truck platform is introduced beneath the platform. In addition the inwardly extending flanges 12^b of the trusses act both as a supporting means for the platform boards and also to receive the upward thrust of the truck platform when elevated to lift the platform and its load.

The platform at opposite sides is supported by means of legs 13. Each leg comprises a vertical bar formed from channel iron. Each channel leg therefore comprises a vertical central web 13^a which is positioned back to back with the flange 12^a of the truss, and the leg also comprises vertical flanges 13^b extending outwardly from the central web 13^a. In the construction shown in Figs. 1 and 3, the upper portions of the flanges 13^b are removed or cut off in any suitable manner and the upper portion of the web 13^a bent outwardly to form a lateral flange 13^c which bears against the bottom of the floor. The flange 13^c may be secured to the floor by means of rivets 15 extending through the angle iron binding strip 10 at the edge of the platform. The central portion of the channel 13 is also riveted at 14 to the vertical flange 12^a of the truss.

Each leg also comprises a bar 16 which may be bent into U or V-shape so as to embrace the lower end of the channel 13. The bar 16 therefore forms a flat bearing surface or foot 16^b for the bottom of the leg, and portions 16^a bent into engagement with the outer sides of the channel bar and riveted thereto. The bar 16 is bent outwardly to provide diverging side portions 16^c which are twisted as shown in Figs. 1 and 3 to bring the upper portions substantially in the plane of the guide flange 12^a; these portions are riveted at 17 to this guide flange. The upper ends of the side members 16^c may be bent outwardly to provide horizontal portions 16^d bearing against the bottom of the floor and bolted thereto at 18.

Referring to Fig. 4, the platform is constructed in substantially the same manner as above described, having a load supporting floor and supporting trusses 12 as shown in Figs. 1 and 3. In this instance each leg comprises a vertical channel bar 13 having the central web positioned back to back with the guide portion 12^a of the truss and riveted

thereto at 14. Each leg in Fig. 4 also comprises a bar 19 which is bent into substantially U or V-shape to embrace the lower end of the channel 13. The bar 19 therefore forms a flat bearing foot 19^b and vertical side portions 19^a abutting against the opposite sides of the channel and riveted thereto at 24. From this point the bar 19 is bent outwardly to provide diverging side or brace members 19^c, the upper edges of which abut against the outer face of the guide flange 12^a. The upper ends of the sides 19^c are oppositely bent in the direction of the length of the platform to provide attaching flanges 19^d extending beneath the ends of the floor boards and these parts are secured to the floor by means of bolts 20. The sides 19^c may also be secured to the truss 12 by means of angle plates 21, one flange of the plate being riveted to the side members 19^c at 22, and the other flange riveted to the guide flange 12^a at 23.

Referring to Figs. 5 and 6 each supporting leg for the platform also comprises a vertical channel bar 13 having the central web thereof positioned back to back with the truss 12. In this instance a gusset plate 25 is interposed between the channel 13 and the flange 12^a of the truss. The leg is riveted at 28 to the gusset plate below the truss flange 12^a, and the upper end of the leg is riveted at 29 to both the gusset plate and the truss. The lower end of the leg is provided with a flat foot portion comprising a strip or bar 30 extending across the bottom of the channel and having side portions 30^a riveted at 31 to opposite sides of the channel.

From the foregoing it will be seen that I have provided a platform of strong and durable construction, capable of sustaining varying loads and of distributing the load so as to prevent the platform from buckling or breaking when engaged by the lift platform of a truck. In addition the platform is provided with legs capable of sustaining heavy loads within a wide range, and also capable of sustaining blows and impacts resulting from collisions by the truck platform or other shocks to which the legs are subjected in use.

What I claim is:

1. In a portable platform the combination of a load supporting floor, a pair of angle bars extending beneath said floor in parallel relation, each angle bar having a vertical guide flange for a truck and an inwardly extending flange to receive the upward thrust of the truck, a gusset plate secured to the outer side of each vertical flange and having an outwardly extending flange for supporting the floor, and a channel formed leg secured to each gusset plate.

2. In a portable platform the combination of a load supporting floor, a pair of angle bars extending beneath said floor in parallel relation, each angle bar having a vertical

guide flange for a truck and an inwardly extending flange to receive the upward thrust of the truck, a gusset plate secured to the outer side of each vertical flange and having an outwardly extending flange for supporting the floor, and a leg comprising a channel member of substantially less width than said gusset plate and having the central web of the channel positioned back to back with respect to said gusset plate and secured thereto.

3. In a portable platform, a load supporting floor comprising a series of cross boards, parallel truss members angular in cross section extending along opposite under sides of said floor, gusset members secured to the outer faces of the truss members and each including an outwardly extending horizontal flange for supporting the floor, and a vertical channel member having the central web thereof secured to the outer face of said gusset member.

4. In a portable platform, a load supporting floor comprising a series of cross boards, parallel truss members angular in cross section extending along opposite under sides of said floor, and a leg structure comprising a gusset member and a vertical channel member, the gusset member having greater width than said channel and extending below the truss member to stiffen the channel member.

5. In a portable platform, in combination, a load supporting floor, parallel truss members angular in cross section extending longitudinally along opposite under sides of the floor, and a leg structure comprising a gusset member abutting against and secured to the outer side of a truss member and having an outwardly extending flange supporting the floor and also comprising a leg member secured to the outer side of the gusset member beneath said flange.

6. In a portable platform, in combination, a load supporting floor, parallel truss members angular in cross section extending longitudinally along opposite under sides of the floor, and a leg structure comprising a gusset member having a flat web abutting against and secured to the outer side of a truss member and having at its upper edge a flange extending outwardly from said web in parallelism with the undersurface of the floor and serving to support the latter and also comprising a leg member secured to the outer side of the gusset member web beneath said flange, said gusset member extending below said truss member to stiffen the leg.

In testimony whereof I affix my signature.
ROBERT T. ROMINE.
